UNITED STATES PATENT OFFICE.

PRICE W. ELY, OF JONESVILLE, VIRGINIA.

SHOVEL.

Application filed November 5, 1921. Serial No. 513,015.

To all whom it may concern:

Be it known that I, PRICE W. ELY, a citizen of the United States, and resident of Jonesville, in the county of Lee and State 5 of Virginia, have invented certain new and useful Improvements in Shovels, of which the following is a specification.

This invention relates to shovels especially adapted for removing the dust caused by 10 cutting machines used in coal mines.

In coal mining an electric machine is employed for providing a space beneath a large quantity of coal so that when the coal is blasted it will drop through this space and 15 thereby be broken up.

The machine employed for forming this space beneath a quantity of coal to be blasted causes a large quantity of dust which must be removed before the blasting operation takes place. This dust must be removed prior to the blasting as otherwise it would form a cushion for the blasted coal and the coal would not be broken up but would merely settle on the cushion of dust. Fur- 20 thermore this dust must be removed prior to blasting to prevent a fire or coal dust explosion.

No special means are now provided for this dust removing operation and I have 30 therefore provided a shovel capable of insertion into the space formed by the drilling machine and said shovel is provided with simple means to lift and remove the dust.

A further object of the invention is to pro- 35 vide a shovel as described which is of highly simplified construction, simple to operate and cheap to manufacture.

Other objects and advantages of the in- 40 vention will be apparent during the course of the following description.

In the accompanying drawing forming a part of this application and in which like numerals are employed to designate like parts throughout the same,

45 Figure 1 is a side elevation of the improved shovel in use.

Figure 2 is a fragmentary perspective of the shovel.

50 Figure 3 is a vertical transverse sectional view through the blade of the shovel.

In the drawing wherein for the purpose of illustration is shown a preferred embodi-

ment of the invention, the numeral 5 designates a blade formed from a single blank of flat metal of a suitable shape.

As illustrated particularly in Figure 2 the blank of metal defining the blade is provided adjacent its rear end with a transverse incision defining a partly severed portion rolled to provide a ferrule 8. The ferrule 8 is formed integral with the blade 5 and is arranged between the longitudinal edges of the same and receives the forward portion of a handle 10. Suitable fastening devices 12 are extended through the ferrule and the forward portion of the handle to prevent the handle from being accidentally disconnected.

The dust 14 to be removed by the shovel is of course mounted on the shovel and when the shovel is withdrawn from the space 15 beneath the body of coal 18 the dust also will be withdrawn. It will be observed that the portion of the blade at the side of the ferrule 8 also provides a dust supporting surface and the dust mounted on the space laterally of the ferrule 8 causes the shovel to be overbalanced on that side.

The overbalancing of the shovel permits the same to be readily and conveniently turned when it is desired to discharge the 80 dust from the shovel.

By reason of the blade being flat, the same may be inserted for a substantial distance into the space 15 for removing all of the dust contained therein.

When the space beneath the body of coal 18 has been formed, a quantity of explosives may be introduced into sockets 20 and ignited so as to blast the coal. When the coal has thus been loosened it drops through the space 15 and is thereby broken up. If the dust 14 was allowed to remain in the space 15 it would form a cushion which would prevent effective breaking up of the coal.

Also if the dust 14 was permitted to remain 95 in the space 15 an explosion or fire would be likely to occur.

With reference to the foregoing description taken in connection with the accompanying drawing, it will be apparent that 100 a shovel constructed in accordance with this invention will act as a expeditious means for removing dust from the space beneath the coal and it will also be apparent that by

reason of the shovel being overbalanced on one side the material may be readily discharged.

In practice the handle 10 may be used as a tamping bar for packing mud or the like in the hole 20 subsequent to placing an explosive within the hole.

Having thus described the invention, what is claimed is:

10. 1. A shovel for use in coal mining, comprising a flat blade having its rear portion formed with a transverse incision defining a partly severed portion rolled to provide a ferrule and a handle positioned in said ferrule.
15. 2. A shovel for use in coal mining, comprising a flat blade having its rear portion formed with a transverse incision defining a partly severed portion rolled to provide a ferrule, a handle positioned in said ferrule,

the blade laterally of said ferrule constituting a material supporting means, the material mounted on the blade laterally of said ferrule constituting a means for overbalancing the blade on one side.

25

3. A shovel for use in coal mining comprising a flat metallic blade having its rear portion provided with a transverse incision defining a partly severed portion, said partly severed portion being rolled to provide a ferrule, a handle received in said ferrule and means extending through said ferrule and said handle for connecting the handle to the blade, the portion of said blade laterally of said ferrule constituting a material supporting means whereby the shovel is overbalanced for permitting the shovel to be conveniently turned.
